FIG. 4.

FIG. 2.

INVENTOR

James Herman Abbott

BY

Cyrus N. Anderson

ATTORNEY.

UNITED STATES PATENT OFFICE.

JAMES HERMAN ABBOTT, OF PHILADELPHIA, PENNSYLVANIA.

DENTAL MANDREL.

1,333,054.

Specification of Letters Patent.

Patented Mar. 9, 1920.

Application filed February 28, 1919. Serial No. 279,750.

To all whom it may concern:

Be it known that I, JAMES HERMAN ABBOTT, a citizen of the United States, and a resident of Philadelphia, in the county of 5 Philadelphia and State of Pennsylvania, have invented an Improvement in Dental Mandrels, of which the following is a specification.

My invention has for one of its objects to 10 provide a dental mandrel comprising means, the presence of which enables grinding disks, disk brushes and other like members to be securely fastened so that they will not rotate relatively to their fastening means or 15 relatively to the mandrel when in use.

It is also an object of my invention to 20 provide a construction of dental mandrel the employment of which renders a grinding disk which may be secured thereon more efficient in operation than heretofore, and 25 also prevents the uneven wearing away thereof.

A further object of my invention is to 30 provide a mandrel with means whereby the grinding member secured thereon is slightly yieldingly supported and held.

Other objects and advantages of my invention will be pointed out in the detailed 35 description thereof which follows or will 40 be apparent from such description.

In order that my invention may be readily understood and its practical advantages more fully appreciated, reference may be had to the accompanying drawing in which 45 I have illustrated one form of a convenient embodiment thereof. It will be understood, however, that changes in the details of construction may be made within the scope of the claims without departing from my in- 50 vention.

In the drawing:

Figure 1 is a side elevation of a dental mandrel constructed in accordance with my invention and having attached thereto a 55 grinding disk;

Fig. 2 is a view partly in side elevation and partly in longitudinal section;

Fig. 3 is a view in elevation of the mandrel body; and

Fig. 4 is a similar view of the same with a coiled spring thereon, the grinding disk and attaching means therefor being omitted.

Referring to the drawing: 1 designates the mandrel body or stem having a screw threaded opening 2 in one end thereof for the reception of a screw 3 employed for se-

curing and retaining a grinding disk 4 or other like member in place. It will be understood that there may be substituted for the grinding disk a disk brush or other polishing member such as are in common use by dentists.

5 designates a metal spring, one end of which extends through an opening 6 through the mandrel body 1, which opening is located a distance below or beyond the inner end of the longitudinal screw threaded opening 2. In constructing the mandrel, the end portion of the wire which is to be inserted into the opening 6 is tapered or reduced and is then inserted. Thereafter the wire is coiled around the upper or outer end portion of the mandrel body as shown in the drawing, the coils terminating a short distance, usually about two coils, beyond the end of the mandrel body or stem as is clearly shown in the drawing. In this coiled wire the coils or turns should be close together, although not directly and firmly in contact. As constructed the coils of the wire are so close together that with the naked eye of usual strength and clearness the spaces between the coils are not discernible, but by the employment of a magnifying glass it is apparent that the coils are not directly in contact. It is desirable, although not absolutely essential, that the coils should be slightly separated in order that there may be a certain amount of resilience or give in the coiled wire during the operation of the mandrel in use. If the coils were in actual rigid contact there would perhaps be no appreciable give or resilient effect, and certain of the advantages which are found to be present in a mandrel constructed in accordance with my invention would not be present or apparent.

The grinding disk 4 or other member, such as above suggested, is held in place by the head of the screw 3 with its inner side in contact with the outer end of the coiled spring 5. Such outer end is squared in any suitable manner as indicated in the drawing so as to form a firm, smooth seat for the adjacent contacting side of the grinding disk or other like member.

In the use of mandrels as heretofore constructed in which a mandrel body is employed without the presence of a coiled spring such as 5, the grinding disk such as 4 or other member is seated directly against the end of such body and is held in such

position by means of a screw such as 3. However, it is found that not infrequently such grinding disk or other similar member is not so securely held but that it will rotate relatively to the mandrel and to the attaching means. I have found that in a mandrel embodying my invention in which the disk or other like member is seated and held against a coiled spring as described, this does not occur because the spring, coacting with the attaching means, seems to have a tendency to grip and hold the grinding disk or other like member so that it is held firmly against rotation with respect to the mandrel or to the attaching means.

It is a known fact that in the employment of grinding disks such as that shown in the drawing it will happen that the peripheral 20 grinding edges thereof will wear away unevenly, leaving a projection here or a projection there. When this condition occurs and it is attempted to use the grinding disk such projections seem to strike the tooth surface which is being ground and to cause a sort of bouncing or bounding movement of the mandrel with the result that the operation is unsatisfactory and the cutting action of the disk slow because of such bouncing 30 movement or lateral vibration. I have found that a mandrel constructed in accordance with my invention avoids the occurrence of this condition. For some reason or other the surfaces of the grinding disks 35 when employed upon a mandrel embodying my invention are worn away evenly and smoothly. I have also found that for some reason or other a grinding disk mounted upon a mandrel constructed in accordance 40 with my invention cuts more rapidly than does one mounted upon the ordinary mandrel in common use in which no spring such as employed by me is present.

I have been unable to determine with 45 definiteness the exact reason or cause for such improvement in the efficiency of the device. It may be by reason of the additional weight of the spring or it may be by virtue of the combined presence of such additional weight and the fact that the grinding 50 disk is slightly yieldingly supported.

Although I have suggested certain possible causes for the increased efficiency of and for the results accomplished by my invention, it is to be understood that my invention is not to be limited in its extent or 55 scope by reason of such reference.

The term "grinding disk" when employed in the claims is intended to comprehend and include not only a disk like that shown in the drawing, but other disks of like character, such as disk brushes, employed by dentists.

I claim:

1. A dental mandrel comprising a body 65 portion provided with a coiled spring member extending beyond said body portion, means for preventing rotation of said coiled spring upon said body portion, and means for securing a disk in contact with the extended portion of said spring member.

2. A dental mandrel comprising a rod, a wire connected at one end to the said rod a distance from one end of the latter and coiled from its point of connection around the said rod, said coil extending to a point beyond the end of said rod, and means for securing a disk in contact with the outer end portion of said coiled wire.

3. A dental mandrel comprising a rod 80 having a screw threaded opening in one end thereof, a wire connected with the said mandrel and coiled around the end portion thereof which is provided with the said opening, the said coiled wire extending a short distance beyond the end of the said rod, and means adapted to engage the said screw threaded opening for attaching a grinding disk to the said mandrel.

4. A dental mandrel comprising a rod 90 having an opening extending transversely therethrough, a coiled spring having its inner end extending into said opening, the said spring being coiled closely about the adjacent end portion of the said rod and the 95 coils of said spring being in close proximity to each other and the said spring terminating approximately a couple of coils beyond the end of said rod.

5. In a dental mandrel, the combination 100 of a mandrel stem or body, a grinding disk, resilient means interposed between said grinding disk and said stem or body, the said grinding disk being seated against the said means and being out of contact with the said stem or body, and means for attaching the said grinding disk to the said stem or body and for clamping and holding the same against the said resilient means, substantially as described.

In testimony that I claim the foregoing as my invention I have hereunto set my name this 25th day of February, A. D. 1919.

JAMES HERMAN ABBOTT.
